(57) **CLAIM**

The ornamental design for an air deflector system for a V-blade snow plow, as substantially shown and described.

DESCRIPTION

The present application is related to commonly-owned and co-pending U.S. application Ser. No. 29/777,773, entitled Air Deflector System for V-Blade Snow Plow, filed on the filing date hereof, and to commonly-owned U.S. application Ser. No. 29/719,577, entitled Fully Adjustable Air Deflector System for Snow Plow Blades, filed on Jan. 6, 2020, which applications are incorporated herein by reference in their entireties.

The present application is also related to commonly-owned U.S. Pat. Nos. 9,551,122 entitled Fully Adjustable Air Deflector System for Snow Plow Blades, issued on Jan. 24, 2017, D851,686, entitled Fully Adjustable Air Deflector System for Snow Plow Blade, issued on Jun. 18, 2019, and D781,347, entitled Fully Adjustable Air Deflector System for V-Blade Snow Plow, issued on Mar. 14, 2017, which patents are incorporated herein by reference in their entireties.

FIG. 1 is a bottom-front perspective view of an air deflector system for a V-blade snow plow of the present invention; FIG. 2 is an upper-front perspective view of a pair of air deflector systems for a V-blade snow plow of the present invention;

FIG. 3 is a left side view thereof;

FIG. 4 is a right side view thereof;

FIG. 5 is a top view thereof;

FIG. 6 is a bottom view thereof;

FIG. 7 is a front view; and,

FIG. 8 is a rear view thereof.

The broken lines shown represent environmental subject matter and form no part of the claimed design.
